DESIGN.

S. N. GOODMAN.

KNIT FABRIC.

No. 18,600.

Patented Sept. 11, 1888.

UNITED STATES PATENT OFFICE.

SAMUEL N. GOODMAN, OF PHILADELPHIA, PENNSYLVANIA, ASSIGNOR TO
CONYERS BUTTON AND MARTIN L. FINCKEL, OF SAME PLACE.

DESIGN FOR A KNIT FABRIC.

SPECIFICATION forming part of Design No. 18,600, dated September 11, 1888.

Application filed August 13, 1888. Serial No. 282,651. Term of patent 3½ years.

To all whom it may concern:

Be it known that I, SAMUEL N. GOODMAN, a citizen of the United States, and a resident of Philadelphia, Pennsylvania, have invented a new and original Design for a Knitted Fabric, of which the following is a specification.

My design is fully shown in the accompanying photograph.

The background of the fabric is an open network or mesh, across which is a band composed of projecting party-colored loops irregularly disposed and intermingled throughout the extent of the band.

I claim—

The design for a knitted fabric, substantially 15 as described, and as shown in the accompanying photograph.

In testimony whereof I have signed my name to this specification in the presence of two subscribing witnesses.

SAMUEL N. GOODMAN.

Witnesses:

WILLIAM D. CONNER,
HARRY SMITH.
